CHRISTIAN BLUST, OF ST. ALBANS, WEST VIRGINIA.

STEAM VALVE OR GAUGE COCK.

Application filed December 19, 1925. Serial No. 76,492.

This invention relates to certain new and useful improvements in valves or gauge cocks and has for its primary object to provide an improved type of valve structure, more particularly designed for use as a gauge cock for determining the height of water in a locomotive boiler or the like.

Another object of the invention is to provide a valve structure wherein a sectional 10 valve casing threaded at one end into a boiler wall contains a valve member in one section of the valve casing that is disposed between the inner and outer sides of the boiler wall to permit proper functioning of the valve 15 should the valve casing become damaged or broken at any point exteriorly of the boiler wall.

A further object of the invention is to provide in a valve structure of the type 20 above set forth, a casing formed of two sections that are detachably connected together to permit displacement of the outer section with the main valve carried thereby while the inner section carrying an auxiliary valve 25 remains in the boiler wall with the auxiliary valve functioning in the absence of the removed section of the valve casing.

A further object of the invention is to provide a loosely mounted valve at the supported 30 end of the valve casing with a series of terminal and transverse openings in the inner end of the valve casing that lies within the boiler to permit the flow of water and steam around the adjacent valve to prevent 35 the deposit of foreign substances or corrosion upon the valve seat, the valve being constructed whereby surging of water within the boiler will effect rotation thereof and insure a perfect working condition of the 40 valve at all times.

With the above and other objects in view that will become apparent as the nature of the invention is better understood, the same 45 consists of the novel form, combination and arrangement of parts hereinafter more fully described, shown in the accompanying drawing and claimed.

In the drawing, wherein like reference characters designate corresponding parts 50 throughout the several views,

Figure 1 is a longitudinal sectional view of a steam valve or gauge cock constructed in accordance with the present invention, the same being illustrated as mounted in a 55 wall of a locomotive boiler,

Figure 2 is a cross-sectional view taken on line 2—2 of Fig. 1,

Figure 3 is a perspective view of the auxiliary valve at the supported end of the valve structure, and

Figure 4 is a side elevational view, partly in section of a modified form of main valve and valve stem.

In the accompanying drawing, which shows preferred embodiments of the invention, there is illustrated a steam valve or gauge cock embodying a casing formed of two sections 1 and 2 having tapering abutting ground faces 3, the sections 1 and 2 of the valve casing being connected together by 70 the union nut 4 having a flange cooperating with a flange on the casing section 2 and threaded upon the casing section 1 as illustrated. Registering bores 5 and 6 are formed in the casing sections 1 and 2, while 75 a drain spout or nipple 7 carried by the casing section 1 has a passage therein communicating with the registering bores 5 and 6.

The section 2 of the valve casing is provided with a wrench gripping face 2^a and is externally threaded for a portion of its length as at 8 for threaded reception in the side wall 9 of a locomotive boiler or the like. The free terminal end of the casing section 80 2 is annularly reduced as at 10 and externally threaded to receive the side flange 11 of an end cap 12. A valve chamber 13 is formed at the inner end of the casing section 2 and has a conical valve seat 14 communicating 90 with the bore 6. A freely mounted valve 15 shown in detail in Fig. 3 is loosely disposed in the valve chamber 13 as shown in Fig. 1 and has a tapering valve head 16 to engage the conical valve seat 14, the valve 15 being 95 normally spaced from its seat by devices presently to be described. As shown more clearly in Figs. 1 and 2, the side flange 11 of the end cap is provided with a circular series of radial openings 17 while a circular 100 series of openings 18 are formed in the outer end wall of the cap. With the valve structure positioned as illustrated in Fig. 1, and with the valve 15 freely disposed in the chamber 13, steam and water surging in the 105 boiler will circulate through said chamber by passing through the openings 17 and 18, and said valve having a series of longitudinally extending grooves 19 in the peripheral wall thereof, will be engaged by the passage of 110

steam and water through the chamber 13 and cause a rotation of said valve to dislodge foreign substances from the walls of the chamber to maintain the same in a clean condition at all times. It will be noted that the reduced end 10 of the inner end of the casing section 2 is disposed entirely within the body of the boiler and the end cap 12 thereon with its side flange 11 being of a diameter smaller than the opening in the boiler wall 9 that receives the valve casing section, will permit free passage of the cap through the boiler opening and permit threaded engagement between the valve casing section 15 on the boiler. It will also be noted that the chamber 13, valve 15 and valve seat 14 being positioned inwardly of the outside of the boiler wall 9, injury to the valve casing section 2 exteriorly of the boiler wall will not 20 affect the operation of the valve 15 in closing upon its seat, as these parts are remotely positioned from points where injury thereto might result.

The valve casing section 1 being detachably connected to the casing section 2 through the provision of the union nut 4 as previously described, carries an internally and externally threaded sleeve 20 alined with the wall 5 and into which the spindle 21 of the operating handle 22 is threaded. A packing nut 23 through which the operating spindle 30 slidably extends is threaded onto the sleeve 20 and the usual packing elements 24 are interposed between the end of the sleeve 20, 35 the packing nut and spindle.

The main valve of the device, as shown in Fig. 1 embodies a cylindrical body portion 25 provided with a conical valve head 26 with valve stems 27 and 28 projecting in opposite directions therefrom, the valve head 26 being associated with the conical valve seat 29 at the inner end of the bore 5. The valve stem 28 is received in the socketed end 30 of the operating spindle and has a kerf 31 in the end thereof for purposes presently to appear. The opposite valve stem 27 projecting through the bores 5 and 6 of the casing sections 1 and 2 engages the apex of the conical valve head 16 of the valve 15 when 40 the main valve 26 is closed as shown in Fig. 1 for unseating the auxiliary valve 15.

In the modified form of main valve as shown in Fig. 4, the valve body 25^a having the tapered head 26^a has the stem section 27^a thereof removably threaded in the valve head as at 32.

When the valve members 25 and 15 are in the positions shown in Fig. 1, the valve 15 is unseated and steam pressure or water in 60 the boiler may move into the chamber 13 and bores 6 and 5 of the casing sections 2 and 1 as far as the seated valve head 26. The valve 25 is retained in its closed position by the adjacent end of the spindle 21 engaging 65 the rear end thereof, and when said spindle

is reversely rotated, water or steam pressure from the valve head 26 will unseat the same and permit either steam or water to escape through the bores 6 and 5 to the bore in the drain 7. The valve 15 being spaced from 70 its seat by contact with the adjacent end of the stem 27 and being under pressure within the boiler, will move toward its seat 14 during unseating movement of the valve 25, therefore, upon continued reverse rotation of the spindle 21 the main valve 25 will be entirely unseated and the valve head 16 will close upon its seat 14. With the valves 15 and 25 so positioned, the union nut 4 may then be operated to disengage the valve casing sections 1 and 2 to permit removal of the section 1 with the valve 25 carried thereby and when necessary, the packing nut 23 and spindle 21 may be disengaged from the valve casing 1 and a suitable implement, such as 80 a screw driver engaged with the slotted end 31 of the valve stem 28 to grind the conical valve head 26 upon its tapering seat 29.

The valve head 25 may then be removed if desired and the ground face connections between the casing sections 1 and 2 ground upon each other. It will be noted that with the casing section 1 removed with the main valve 25 carried thereby, the auxiliary valve 15 engaging the conical valve seat 14 in the casing section 2 closes the interior of the boiler to the atmosphere which renders it unnecessary to exhaust steam from the boiler when working upon the casing section 1 and the valve 25 carried thereby. If desired, the 100

type of valve shown in Fig. 4 may be employed with the tapering valve head 26 ground upon the seat 29 while the casing sections 1 and 2 remain in coupled condition, it being necessary only to remove the valve 25^a and disconnect the stem 27^a. In a similar manner, the casing section 2 may be removed from the boiler wall 9 and upon removing the end cap 12 a screw driver or like implement engaged in the slot 15^a in the head of 110 the valve 15 may grind the valve head 16 upon its seat 14. An official steam engineering test requires that a wire or similar implement be capable of free passage entirely through the valve casing and this operation 115 may be effected without removing the casing section 2 from the boiler. During this test, steam is exhausted from the boiler, the casing section 1 disengaged from the section 2 and a wire passed through the bore 6 of the 120 casing section 2 will extend around the valve 15 for passing through any one of the end openings 18 in the cap 12.

From the above detail description of the device, it is believed that the construction 125 and operation thereof will at once be apparent, and while there is herein shown and described the preferred embodiments of the present invention, it is, nevertheless, to be understood that minor changes may be made 130

therein without departing from the spirit and scope of the invention as claimed.

What is claimed is:—

1. In a valve structure, a sectional casing, 5 means for detachably connecting the sections together, a valve carried by each section, the outer one of said valves comprising an enlarged head and a reduced stem, said head closely fitting the bore of the outer one of 10 said sections, a threaded valve operating spindle having a socketed end receiving the valve stem with the end of the spindle engaging the valve head to move the same toward its seat, the outer end of the valve 15 spindle having a kerf positioned outwardly of the threaded portion of the stem to permit grinding of the valve directly on its seat.

2. In a valve structure, the combination 20 with a boiler wall of a sectional valve casing

set in the wall, means for detachably connecting the sections together, a valve carried by each section, the outer one of said valves comprising an enlarged head and reduced stem, said head closely fitting the bore of 25 the outer one of said sections, said valve and its seat being positioned intermediate the inner and outer sides of the boiler wall when the device is in use, a threaded valve operating spindle having a socketed end receiving the valve stem with the end of the spindle 30 engaging the valve head to move the same toward its seat, and the outer end of the valve spindle having a kerf outwardly of the threaded portion of the stem to permit grinding of the valve directly on its seat when the spindle is removed. 35

In testimony whereof I affix my signature.

CHRISTIAN BLUST.
